UNITED STATES PATENT OFFICE.

THOMAS B. STANDING AND WILLIAM V. BRAYSHAW, OF FALL RIVER,
MASSACHUSETTS.

DESIGN FOR A WEDGE-BLOCK.

SPECIFICATION forming part of Design No. 27,388, dated July 20, 1897.

Application filed May 25, 1897. Serial No. 638,168. Term of patent 31 years.

To all whom it may concern:

Be it known that we, THOMAS B. STANDING and WILLIAM V. BRAYSHAW, of Fall River, in the county of Bristol and State of Massachusetts, have invented and produced a new and original Design for Wedge-Blocks for Rope-Clamps, of which the following is a specification, reference being had to the accompanying drawings, forming part thereof.

Figure 1 represents a side elevation of a wedge-block illustrating our invention. Fig. 2 represents a cross-sectional view of the same, taken on a line $x-x$, Fig. 1.

The leading feature of our new design for wedge-blocks consists in the design as herein shown and described.

In the drawings the inclined arm 5 is flat on its upper and lower surfaces to 6 and 7.

From 6 the vertical outline curves upward to 8, then extends in a straight line to 9, from whence it curves downward below the point 7, and again upward to meet that point. The outline of the head in plan view is generally circular, but is slightly flattened between the points 10 and 11. On this face are the corrugations 12, extending from the flat upper surface and following the curved contour of the lower portion of the head.

What we claim is—

The design for a wedge-block for rope-clamps as herein shown and described.

THOMAS B. STANDING.

WILLIAM V. BRAYSHAW.
